UNITED STATES PATENT OFFICE.

DELANCEY E. HUNTLEY AND WILLIAM H. BENTINE, OF WELLSTON, OHIO.

ELECTRIC AUTOMATIC BOWLING-ALLEY.

1,151,269.

Specification of Letters Patent. Patented Aug. 24, 1915.

Application filed November 18, 1914. Serial No. 872,780.

To all whom it may concern:

Be it known that we, DELANCEY E. HUNTLEY and WILLIAM H. BENTINE, citizens of the United States, residing at Wellston, in the county of Jackson, State of Ohio, have invented a new and useful Electric Automatic Bowling-Alley, of which the following is a specification.

The present invention relates to improvements in an electrically actuated bowling alley, one object of the invention, being the provision of an alley of this kind in which each pin when in normal position maintains an open circuit, this circuit to be closed when the pin is struck or moved by a ball thrown by the player to in turn permit the closing of the circuit to indicate the number of the pin effected and also assist in connecting other circuits whereby all pins operate an audible alarm and at the same time insure the proper closing of the circuit to return the pins to normal position.

A further object of the present invention, is the provision of a box ball of this character, in which the pin when in normal position maintains a circuit controlling lever in such position that the various circuits in the apparatus are maintained open, the same being disposed to be closed or in a position to be readily closed when the pin is moved to abnormal position due to being hit by a thrown ball, there being further provided, a pin resetting device which is selected by the falling pin and finally manually controlled at the end of the play to return the pins to normal position.

A still further object of the present invention, is the provision of a simple mechanism of this character, by means of which electrical connection may be made from the lighting circuit within the house or residence, and whereby the mechanism controlled by the pin may be automatically operated to display the various audible and visual signals which are finally returned to normal position when the pins are actuated electrically to be reset.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed with-

out departing from the spirit of the invention.

In the drawings—Figure 1 is a cross section through the alley adjacent the pin supporting portion of the same, such portion being in front elevation. Fig. 2 is a top plan view of the rear portion of the alley showing the pins in normal position. Fig. 3 is a side elevation of approximately the portion of the mechanism shown in Fig. 2. Fig. 4 is a longitudinal cross section through the switch carrying casing of the present invention showing the various parts in the positions they assume when the pins are in both normal and abnormal positions. Fig. 5 is a diagrammatic perspective view of one of the pin controlled levers with the pins moved thereaway from to clearly show the operation of the same. Figs. 6 and 7 are detailed sectional views through one of the pins. Fig. 8 is a plan view of the pin setting disk. Figs. 9 and 10 are detailed views of the magnetic switch used for controlling the motor in operating the pin setting disk. Fig. 11 is an electrical diagram of the complete alley.

Referring to the drawings, the numeral 1 designates the ball receiving portion of the alley, which at the rear end thereof is provided with the upstanding casing or supporting portion 2 at the forward portion of which is projected the two arms 3 in which is fixedly mounted a shaft or rod 4. This shaft or rod 4 has disposed upon it at equidistant points, frictional sleeves 5, which carry each a pin 6. A set screw 7 is provided for locking the sleeve relatively to the pin while disposed between the pins are the frictional sleeves 8 which are locked in position by means of the set screws 8' so that the pins may be frictionally bound upon the rod 4 so as to not be readily moved from the full to the dotted line position, as shown in Fig. 4, the friction of such members being sufficient to maintain the pin in the dotted line position until set, as will presently appear. Carried by and projecting from the rear face of the head of each pin is a strip 9 of insulation, which constitutes as will presently appear, the means for permitting the various circuits to be selected.

Mounted within the casing 2 are a plurality of levers 10, the same being constructed and arranged as shown in Figs. 4 and 5 so as to have horizontal swinging movement upon the pivots 11, a spring 12 being disposed

thereupon to normally hold the contact end 13 toward the contact 14 carried by the plate 15, the block or strip 9 of insulation when the pin 6 is in a vertical position being disposed to be interposed between the end 13 and the block 14 and thus maintain an open circuit at such point.

When the pin 6 is struck by a thrown ball, and is moved from the dotted to the full line position, as shown in Fig. 4, the following circuit, as illustrated in the diagram in Fig. 11, is closed. This circuit includes the source of electrical energy B, which may be a generator, a battery, or may be connected with an ordinary lighting circuit, the conductor 16, the conductor 17, the contact portion 13 of the lever 10, the contact 14, the support 15, the knife switch 18, the conductor 19, the signal lamp 20, which is disposed to illuminate the transparent numeral sign 20' carried by the upper portion of the casing 2, the conductor 21, and the conductors 22 and 23. Thus the light 20 is energized and the player knows at a glance which pin has been upset.

In order to provide a means for operating a switch by the lever 10 when the pin is upset and consequently select a circuit for the operation of the pin resetting motor 36, a bar 24 is mounted upon brackets 24' carried within the casing for longitudinal sliding movement, a spring 25 being connected thereto, to normally hold the bar 24 so that the contact end 27 thereof will be out of engagement with the sheath 28 which with the end 27 constitutes the switch, a lug 26 being carried by the bar 24, one to every lever 10, so that when one lever is operated, the bar 24 is moved to cause the end 27 to engage the sheath 28 and is there held until the lever or levers 10 are returned to their normal position with the block 9 of insulation between the contact portions 13 and 14.

In order to provide a means whereby the pin resetting motor may be energized selectively by the operator or player at the playing end of the alley, there is disposed at such end, a casing 38, with the spring propelled button 37 which in turn is in coöperable relation to the armature switch 34, there being further disposed within the casing 38, the electromagnet 30 which is disposed to influence the armature 34 when the following circuit is closed, due to the closure of the switch 27 and 28 and to the manual depression of the button 37, and the consequent movement of the armature 34 toward the electromagnet 30. This circuit includes the battery B, the conductor 16, the end 27 of the bar 24, the sheath 28, the conductor 29, the electromagnet 30, the conductor 31, the spring propelled contact member 32 which is disposed in the path of to be engaged by the pin 33 carried by the armature 34, the conductor 35, the pin resetting motor 36, and

the conductor 23. It will thus be seen that when the armature 34 is moved by the pin 37, that the contact member 33 will engage the spring propelled contact 32 and thus close the above circuit so that the electromagnet 30 will be energized and thus maintain the armature 34 in such closed position until the bar 50 is operated to reset the pins and the springs 12 operate the various levers 10 and consequently release the bar 24 to its spring 25 to open the circuits at 27 and 28 to permit of the deenergization of the electromagnet 30 and the release of the armature 34 away from the electromagnet 30.

In order to insure the holding of the armature 34 after the initial closure of the contacts 32 and 33, and the motor has attained full speed and therefore the coil is being less affected, the wipe contacts 39 and 40 are provided and arranged, as shown in Fig. 9.

In the present apparatus, when the player has upset all of the pins, the audible alarm or bell 47 is energized, this being accomplished by means of the series of contact plates 41, there being one to each lever 10 so that the resilient bridging member 42, which is carried by the end of each lever 10 and insulated at 43 therefrom, will be bridged from left to right as viewed in Fig. 11 until the extreme one at the right has engaged the contact plate 45. When this is accomplished, the following circuit is closed and includes the battery, the conductors 16 and 44, the contacts 41 and bridging contacts 42, the contact 45, the conductor 46, the bell 47, and the conductors 22 and 23. In this manner, the bell 47 will continue to ring until the levers are properly reset to the normal position, as shown in Fig. 11.

The pin resetting mechanism, includes a shaft 48, which is mounted for oscillation and as shown in Fig. 4, carries the depending arms 49 one at each side of the same and adjacent the respective arms 3, said shaft also being journaled through the arms, while upon the extreme free end of the arms 49 is carried the resetting plate 50 which normally assumes the full line position, as shown in Fig. 4, to be moved to the dotted line position and thus reset the pin from its dotted to full line position.

In order to provide a means for operating the shaft 48 and consequently the resetting plate 50 both from full to dotted line position and vice versa, there is fixed upon the shaft 48 a disk 52, this disk 52 being normally actuated in one direction for a distance of approximately 90 degrees by means of the arm 53 which extends radially therefrom and carries thereupon, the adjustable weight 54. Pivoted at 55 upon the outer face of the disk 52 is a swinging member 56 whose tension is adjusted by means of the spring controlled member 57 so that the pin engaging end 58 thereof may have the ten-

sion thereof regulated according to the need, the pin 59 being carried by the large gear 60 which is freely rotatable upon the shaft 48 at one side of the disk 52. It will thus 5 be seen that as the gear 60 is moved to carry the pin 59 in the direction of the arrow as shown in Fig. 8, that the pin will engage the end 58 of the pawl 56, and consequently move the disk 52 and shaft 48 therewith, 10 this action causing the pin resetting plate 50 to be moved from the full to dotted line position, at which time, the arms 49 come in contact with the abutting pins 51 which offer sufficient resistance to permit the pin 59 to 15 upset the pawl 58 against the action of the spring 57, the pin 59 thus passing beyond the pawl 56 and releasing the disk 52 and consequently the shaft 48 and pin resetting plate 50 to the action of the weight 54 which 20 thus returns the parts from the dotted line to the full line position in Fig. 4, with the plate 50 out of the way to permit the pins 6 to be moved to the dotted line position.

The motor 36 is provided to operate the 25 gear 60, and is provided with the shaft 61, upon which is fixed the worm 62 which is in mesh at all times with the gear 60 as clearly illustrated in Fig. 3. Thus when the circuit is closed by the switch member 32 and 33, 30 the switch at 27 and 28 being closed, the motor 36 is set in operation and in turn through the worm gear 62 rotates the gear 60 and as before stated causes the pin 59 to operate the disk 52 and the resetting plate 50.

35 In order to provide a means for producing a braking action upon the gear 60 so that the same will be stopped after having been moved one full revolution so that the pin 59 will be presented in the proper position for again engaging the end 58 of the pawl 56, a disk 63 is fixed fast upon the gear 60 and is provided with the recessed portion 64 in the periphery thereof, having the rounded cam portion 65 to permit of the 40 roller 66 after passing into the recess 64 to pass thereout of upon the concentric portion of the disk 63, thus causing the brakes to be applied and released sufficiently to bring the shaft 61 and the gear 60 to a full stop.

45 The roller 66 is carried in the free end of the pivoted lever 67 which is mounted with its lower end in the lug 68 while the pin 70 connects the link 71 to the lever 67 intermediate of its ends, there being connected 50 to the lever, a spring 69 which normally holds the roller 66 in engagement with the periphery of the disk 63.

The link 71 is connected to one end of the bell crank lever 72, which is pivoted at 73 and has its opposite end connected to the brake controlling member 73' which is pivoted in the support 74, the same being provided with the brake shoe 75 disposed in co-operable relation with the brake drum 76 55 which is fixed upon the shaft 61. A spring

77 is connected to the bell crank lever 72 to normally hold the brake shoe 75 upon and in contact with the brake drum 76.

In the operation of the present device, the player standing at the proper end of the 70 alley throws the ball, as is the usual custom in bowling, and endeavors to hit one or more pins 6 in the row at a point below the rod 4, this action, as before stated, causing the pin 6 to be moved from the position shown in 75 full lines to that shown in dotted lines in Fig. 4, and thus permitting the lever 10 to be released and to close the circuit at contacts 13 and 14. As one pin at a time is engaged, the respective visual signal lamps 20 80 are energized and if all pins at the respective "go" or play of the players are upset, the audible alarm 47 is energized.

At the end of the play if any of the pins have been upset, the switch at 27 and 28 has 85 been closed, and it is simply necessary for the operator to push upon the button 37 and cause the closure of the circuit at contacts 32 and 33, at which time, the coil 30 is energized and holds the armature switch 34 closed so that 90 the operator merely has to depress the pin 37 once to release it instead of maintaining the same closed manually. When this circuit is closed, the pin resetting motor 36 is operated to in turn rotate the gear 60 and consequently 95 the disk 52 until the same has moved approximately 90 degrees, at which point the pin resetting plate 50 has assumed the dotted line position and engages the arms 51 which retard the action of the pin resetting 100 member 50 and its disk 52 and thus permits the pin 59 of the gear 60 to pass beyond and continue in its rotation, the weight 54 returning the pin resetting plate 50 from the dotted to full line position as shown in Fig. 4, while the gear 60, due to the momentum of the motor 36, travels on until halted by the brake actuating lever 67 due to the recess 64 in the disk or cam 63. As before 105 stated, this disk 63 is so constructed as to 110 permit the roller 66 to enter the recess sufficiently to slow down the shaft 61 and before the same is brought to a halt to permit the disk 63 to have its rounded portion 65 engage the roller 66 and thus release the 115 brake due to the movement of the lever 67 when the roller 66 engages the concentric periphery of the cam 63.

When the various pins 6 are moved from the dotted to full line positions, the circuit opening blocks 9 of insulation were disposed between the contact portions 13 and 14 of the various switch controlling members 10 and such levers or members 10 were returned to open circuit position to thus 120 open the circuit to the bell 47, the switch at 27 and 28, and the circuit, as before stated, between the contacts 13 and 14. Thus all of the parts are automatically returned to their 125 normal positions simultaneously with the 130

resetting of the pin 6, such operation being set in motion due to the operation of the button 37 which is disposed at the forward end of the alley and in ready reach to the players.

Although only five pins have been shown it is apparent that any number of pins may be employed, and that such pins may be arranged instead of in a row, as illustrated in 10 triangular shape as is the usual practice in bowling alleys.

What is claimed is:

1. A game apparatus having a ball course over which balls are adapted to be rolled, a 15 plurality of independently frictionally fulcrumed pins mounted to be maintained in set or upset position, a pin resetting mechanism, means controlled by each pin for connecting for operation the pin resetting mechanism as a pin is upset, and manually operable means for setting in operation the resetting mechanism after a pin has been upset.

2. A game apparatus having a ball course over which balls are adapted to be rolled, a 25 plurality of independently frictionally fulcrumed pins mounted to be maintained in set or upset position, a pin resetting mechanism, means controlled by each pin for connecting 30 for operation the pin resetting mechanism as a pin is upset, manually operable means for setting in operation the actuation of the pin resetting mechanism after a pin has been upset, and a signal device for each pin.

3. A game apparatus having a ball course over which balls are adapted to be rolled, a 35 plurality of independently frictionally fulcrumed pins mounted to be maintained in set or upset position, a pin resetting mechanism, 40 means controlled by each pin for connecting for operation the pin resetting mechanism as a pin is upset, manually operable means for setting in operation the actuation of the pin resetting mechanism after a pin has been upset, and a visual signal device for each pin operated by the movement of the pins.

4. A game apparatus having a ball course over which balls are adapted to be rolled, a 50 plurality of independently frictionally fulcrumed pins mounted to be maintained in set or upset position, a pin resetting mechanism, means controlled by each pin for connecting for operation the pin resetting mechanism as a pin is upset, manually operable 55 means for setting in operation the actuation of the pin resetting mechanism after a pin has been upset, a visual signal device for each pin operated by the movement of the pins, and an audible signal device set in 60 operation when all pins have been upset.

5. A game apparatus having a ball course over which balls are adapted to be rolled, a 65 plurality of independently frictionally fulcrumed pins mounted to be maintained in set or upset position, a pin resetting mecha-

nism, means controlled by each pin for connecting for operation the pin resetting mechanism as a pin is upset, manually operable means for setting in operation the actuation of the pin resetting mechanism after a pin 70 has been upset, a visual signal device for each pin operated by the movement of the pin, and an audible signal device controlled by the pins and set in operation only when all of the pins have been upset. 75

6. A game apparatus, having a plurality of swingingly mounted frictionally held pins, a block of insulation carried by each pin, a visual electric signal for each pin, a normally opened switch for each signal, said 80 block of insulation when the pin is upright separating the switch to maintain it open and for permitting the switch to close when the pin is upset, and an electric circuit including a source of electrical energy, said 85 signal and said switch.

7. A game apparatus, having a plurality of swingingly mounted frictionally held pins, a visual electrical signal for each pin, a switch for each signal, means carried by 90 each pin for maintaining the switch open when the pin is set and for permitting the switch to close when the pin is upset, an electric circuit including a source of electrical energy, said signal and said switch, an 95 audible electric signal, a plurality of switches, one controlled by each of the first switches and all of said second switches co-operating to form a closure for the audible signal, and a circuit including a source of 100 electrical energy, the audible signal, and all of the second switches and to be energized only when all of the second switches are serially connected.

8. In a game apparatus, having a plurality of swingingly mounted frictionally held pins, a visual electric signal for each pin, a switch for each signal, means carried by each pin for maintaining the switch open when the pin is set and for permitting the 105 switch to close when the pin is upset, an electric circuit including a source of electrical energy, said signal and said switch, an electric motor, a switch under the influence of all of the first switches and closed simultaneously with the closure of any one of them, a manually operable switch, a pin resetting mechanism operated by the motor, and a circuit including the motor, and the last two switches, whereby when a pin is 110 upset, the last circuit is effective to be manually closed. 115

9. In a game apparatus, having a plurality of swingingly mounted frictionally held pins, a visual electric signal for each pin, a switch for each signal, means carried by each pin for maintaining the switch open when the pin is set and for permitting the switch to close when the pin is upset, an electric circuit including a source of electrical 125 energy, said signal and said switch, an 130

energy, said signal and said switch, an electric motor, a switch under the influence of all of the first switches and closed simultaneously with the closure of any one of them, 5 a manually operable switch, a pin resetting member mounted for swinging movement at the rear of the pins, and coöperative means carried thereby and the motor whereby the closure of the last switch and the manual 10 closure of the manual switch causes the energization of the motor and the operation of the pin resetting member.

10. In a game apparatus, having a plurality of swingingly mounted frictionally 15 held pins, a visual electrical signal for each pin, a switch for each signal, means carried by each pin for maintaining the switch open when the pin is set and for permitting the switch to close when the pin is upset, an electric 20 circuit including a source of electrical energy, said signal and said switch, an electric motor, a switch under the influence of all of the first switches and closed simultaneously with the closure of any one of them, 25 a manually operable switch, a pin resetting member mounted for swinging movement at the rear of the pin, coöperative means carried thereby and the motor whereby the closure of the last switch and the manual 30 closure of the manual switch causes the energization of the motor and the operation of the pin resetting member, and an auto-

matic brake device for halting the motor after the same has moved a predetermined distance and the pins have been reset. 35

11. A game apparatus having a plurality of frictionally held swingingly mounted pins capable of being upset by a thrown ball, a pin resetting member mounted at the rear of said pin for movement at approximately 90 degrees and for engagement with the pins below the pivotal point of such pins to move them to upright position, and a motor, a gear operably connected to the motor, a disk operably connected to the pin 40 resetting member, coöperative means carried by the gear and the disk, whereby the disk is moved a predetermined distance with the gear to swing the pin resetting member, an abutment disposed in the path of the pin resetting member for limiting the movement of the same in pin resetting position, and an automatic brake device for halting the gear and motor after the gear has rotated approximately one full revolution. 45

In testimony that we claim the foregoing as our own, we have hereto affixed our signatures in the presence of two witnesses.
